UNITED STATES PATENT OFFICE

165,351

THUMB LATCH KEY FOR A GAS SAFETY VALVE

Willis E. Williams, Shelbyville, Ind., assignor to
Chambers Corporation, a corporation of Indiana

Application December 23, 1949, Serial No. 6,801

Term of patent 14 years

(Cl. D81—10)

To all whom it may concern:

Be it known that I, Willis E. Williams, a citizen of the United States, residing at Shelbyville, in the county of Shelby and State of Indiana, have invented a new, original, and ornamental Design for a Thumb Latch Key for a Gas Safety Valve, of which the following is a specification, reference being had to the accompanying drawing, forming part thereof.

Fig. 1 is a top plan view of a thumb latch key for a gas safety valve, showing my new design;

Fig. 2 is a bottom plan view thereof;

Fig. 3 is a side elevation thereof;

Fig. 4 is a front end view thereof; and

Fig. 5 is a back end view thereof.

I claim:

The ornamental Design for a thumb latch key for a gas safety valve, as shown.

WILLIS E. WILLIAMS.
